UNITED STATES PATENT OFFICE.

VICTOR H. JENNINGS AND HERBERT H. WATSON, OF WORCESTER, MASSACHUSETTS, VS
SIGNORS TO CROMPTON & KNOWLES LOOM WORKS, OF WORCESTER, MASSACHUSETTS, A CORPORATION OF MASSACHUSETTS.

DOBBY MULTIPLIER.

Application filed June 21, 1926. Serial No. 117,249.

This invention relates to multipliers of the general type used in connection with loom dobbies and which are adapted to control the motions of the drop boxes and to reduce the length of pattern chain required thereby. This general type of multiplier is well known in the art but as heretofore built has embodied certain constructions which have proved more or less troublesome in actual use.

10 It is the general object of our invention to improve the construction of such multipliers in certain important respects by which these objectionable features are avoided and the utility of the multiplier is increased. 15 With this general object in view, important features of our invention relate to the provision of an improved construction by which certain related parts of the multiplier may be easily adjusted as a unit relative to other parts thereof; to the provision of an improved drive and an improved support or bearing construction for the pinion shaft of the multiplier, and to the provision of means effective to prevent breakage when 20 normal operation of the multiplier is prevented.

Our invention further relates to arrangements and combinations of parts which will be hereinafter described and more particularly pointed out in the appended claims.

30 A preferred form of the invention is shown in the drawings in which

Fig. 1 is a side elevation, partly in section, of our improved multiplier;

35 Fig. 2 is an end view, looking in the direction of the arrow 2 in Fig. 1; and

Fig. 3 is a sectional elevation, taken along the line 3—3 in Fig. 1.

Referring to the drawings, our improved 40 multiplier comprises frame members 10 and 11 in which a cylinder shaft 12 is freely rotatable. The shaft 12 at one end has a bearing block 13 which is adjustable vertically and horizontally in a recess in the frame member 11 by set screws 14 and 15 (Fig. 2).

The shaft 12 is also supported in a bearing block 16 which is similarly adjustable vertically and horizontally in a recess 17 of the frame member 10, such adjustment being accomplished by means of set screws 18 and 19 (Fig. 3). A large gear 20 is secured to one

end of the shaft 12 by a set screw 21 and

is engaged by a pinion 22 on a short horizontal shaft 23 which is connected by bevel gears 24 and 25 with a continuously rotated 55 driving shaft 26.

The set screw 21 is preferably provided with a soft end or nose portion engaging the shaft 21, so that the gear 20 may slip on the shaft 12 if normal rotation of the shaft 12 is 60 prevented. The multiplier is thus effectively prevented from accidental injury by the provision of the yieldable set screw 21.

A cylinder 28 (Fig. 1) for the harness levers is fixed to the shaft 12 and rotates in 65 unison therewith. A drop box pattern chain cylinder 30 is formed on a sleeve 31 which is freely rotatable upon the shaft 12 and which is provided with a star wheel 32 adjacent one end thereof. A multiplier chain cylinder 35 is similarly mounted on a sleeve 36 freely rotatable on the outer end of the shaft 12 and provided with a star wheel 37.

A pinion shaft 38 rotates freely on a bearing 39 in the lower part of the bearing block 75 16 and is provided with a second bearing 40, formed on the end of an arm 41 projecting laterally from the lower portion of the bearing block 16. The pinion shaft 38 is provided with a pinion 42 fixed thereon and engaged and rotated by a gear 43 fast on the cylinder shaft 12. 80

A pin gear 45 is keyed to the pinion shaft 38 and is provided with two driving pins 46, one of which is adapted to engage the 85 star wheel 37 at every half revolution of the pinion shaft 38. A second gear 48 (Fig. 3) is similarly keyed to the pinion shaft 38 and is provided with pins 49 for engagement with the star wheel 32.

Each of the pin gears 45 and 48 is 90 slideable axially into and out of position for engaging its star wheel 37 or 32 by levers and connections controlled from the multiplier and box motion chains in the usual manner, this controlling mechanism forming no part of our present invention.

The outer ends of the shafts 12 and 38 are held in definite spaced relation by a connecting link or floating bearing member 50 (Fig. 1) and the link 50 is held from axial displacement by a collar 51 on the shaft 12. 100

Having described the details of construction of our invention, the advantages there-

of are believed to be clearly apparent. The shaft 12 is rotated regularly by the gear 20 unless normal operation of the multiplier is prevented. In such case, the yielding set screw 21 allows the gear 20 to rotate without turning the shaft, thus protecting all parts of the multiplier mechanism. The sleeves 31 and 36 are mounted at each side of the frame member 10 and do not extend through the bearing block 16, so that no binding of the sleeve in the bearing can take place. The drive for the pinion shaft 38 is taken directly from the shaft 12 through the gears 42 and 43 and the pinion shaft 38 is supported in spaced bearings 39 and 40, both of which are fixed on the bearing block 16, so that adjustment of the block 16 will not change the spaced relation between the shafts 12 and 38.

20 The provision of double pins 46 and 49 for the pin gears 45 and 48 permits the pinion shaft to rotate at one half of the speed which has been heretofore necessary when a single pin was used. Accordingly the pins 25 when engaging the star wheels are moving at only one half of the previous speed and the shock of the engagement is thereby greatly reduced.

While our improvements relate to details 30 of construction, the sum total of their effect is very important and results in the production of a dobby multiplier which is more easily manufactured and much more easily kept in satisfactory working condition than 35 has been heretofore the case.

Having thus described our invention and the advantages thereof, we do not wish to be limited to the details herein disclosed otherwise than as set forth in the claims, but what 40 we claim is:—

1. In a dobby multiplier, a frame, a cylinder shaft, a bearing for one end of said shaft adjustably mounted in said frame, a pinion shaft disposed parallel to said cylinder shaft, and a bearing member provided 45 with a second bearing for said cylinder shaft and with a bearing for said pinion shaft, said bearings being fixed in definite spaced

relation and said bearing member being adjustable as a unit in said frame.

2. In a dobby multiplier, a frame, a cylinder shaft, a bearing member adjustable in said frame and having a bearing for said cylinder shaft, a pinion shaft mounted parallel to said cylinder shaft and having a bearing in said bearing member, and a second bearing for said pinion shaft mounted upon an arm projecting from said bearing member.

3. In a dobby multiplier, a frame member, a cylinder shaft extending through said frame member, a drop box pattern chain cylinder, a sleeve and star wheel for said cylinder rotatable on said cylinder shaft at one side of said frame member, a multiplier cylinder, a sleeve and star wheel for said multiplier cylinder rotatable on said cylinder shaft at the opposite side of said frame member, a pinion shaft extending through said frame member, and pin gears on said pinion shaft mounted at opposite sides of said frame member and positioned for selectively engaging said star wheels.

4. In a dobby multiplier, a frame member, a cylinder shaft extending through said frame member, a drop box pattern chain cylinder, a sleeve and star wheel for said cylinder rotatable on said cylinder shaft at one side of said frame member, a multiplier cylinder, a sleeve and star wheel for said multiplier cylinder rotatable on said cylinder shaft at the opposite side of said frame member, a pinion shaft extending through said frame member, and pin gears on said pinion shaft mounted at opposite sides of said frame member and positioned for selectively engaging said star wheels, said pin gears each having two engaging pins and said gears being set to cause said pins to engage said star wheels alternately and at substantially 90 degrees intervals.

In testimony whereof we have hereunto affixed our signatures.

VICTOR H. JENNINGS.
